ORNAMENTAL DEVICE

Frank Pierce Mortimer, Pottsville, Pa.

Application February 28, 1941, Serial No. 381,171

11 Claims. (Cl. 240—10)

My invention relates to improvements in ornamental devices, and particularly to devices of this character comprising a support and a plurality of relatively small objects supported thereby in a decorative manner wherein light diffusion and reflection are utilized to enhance the attractive and decorative effect, and the primary object of my invention is to provide simple and efficient arrangements of this character which can be provided at relatively low cost.

Other important objects and advantages of my invention will be apparent from a reading of the following description taken in connection with the appended drawings, wherein for purposes of illustration I have shown preferred embodiments of my invention.

In the drawings:

Figure 1 is a general side elevational view of the preferred embodiment showing a plurality of spherical articles displayed thereby.

Figure 2 is a vertically contracted enlarged transverse vertical sectional view taken through the lower part of Figure 1.

Figure 3 is an enlarged top plan view of Figure 2 with the spherical articles removed.

Figure 4 is a plan view of the combined hanger and reflector.

Figure 5 is a vertically fore-shortened side elevational view of the post.

Figure 6 is a side elevational view of the post guide.

Figure 7 is a side elevational view partly in section of a modified form of the invention in which the combined hanger and reflector of the foregoing embodiment is omitted.

Figure 8 is an enlarged top plan view of one of the circular hangers.

Figure 9 is an enlarged fragmentary transverse vertical sectional view taken through an upper part of the post and showing the manner of mounting one of the hangers thereon.

Figure 10 is an enlarged top plan view of the base.

Referring in detail to the drawings, and first to the embodiment of the invention shown in Figures 1 through 6, the numeral 5 generally designates the circular transparent or translucent base which is preferably made of glass. The base comprises a flat top 6 of reduced diameter whose outer edges merge into beveled walls 7 which terminate at their lower edges in short perpendicular walls 8, the bottom of the base being open, and the top provided with a centralized circular opening 9. The lower edge of the wall 8 is designed to rest upon a suitable supporting surface.

Within the opening 9 is an electric bulb 10 mounted in a cylindrical socket 11 mounted on a circular base 12 provided with a laterally projecting switch arm 13. The bulb 10 rises about half way above the top 6. The base portion 12 of the bulb socket is formed with vertical openings 14 at equally circumferentially spaced points for reception of the lower ends of the legs of the post which is generally designated 15 and of the legs of the post guide which is generally designated 16.

The post 15 may suitably comprise a vertical rod 17 which is bent laterally adjacent its lower end at 18 and again bent at 19 to define the leg 20, the leg 21 being constituted by similar bar or rod material bent at the point 22 and joined at the point 23 with the bend 18, the resultant horizontal arms being diametrically aligned. The lower ends of the legs 20 and 21 are received in diametrically opposed holes 14 in the base portion of the bulb socket.

The post guide 16 consists of similar material bent into a U-form and providing respective legs 24 and 25 for reception in the remaining diametrically opposed holes 14 in the base portion of the bulb socket. The bight portion 26 is formed with a central depression 27 to receive the portion of the post constituted by the portions 18 and 23, so as to lend support and rigidity to the resultant structure and form a framework or cage rising concentrically around the bulb 10 as shown in Figure 2.

Concentrically surrounding the base portion 12 of the bulb socket and rising above the top 6 of the base 5 and substantially snugly fitting the opening 9 in the top 6 of the base is the combined hanger and reflector which is generally designated 28. This is formed from a sheet of light reflecting material or from a sheet of some other material painted with light reflecting paint, the sheet being generally rectangular in form as shown in Figure 4 and having spaced tabs 29 at one end for reception in correspondingly placed openings 30 at the opposite end of the sheet. The sheet is provided with transversely elongated longitudinally spaced light passing openings 31. The upper edge 32 of the plate is provided at suitable intervals with hooks 33 which are formed by cutting out portions of the said edge and bending up the resultant tabs into hook form. When the tabs 29 are engaged in the openings 30 the sheet has a cylindrical form illustrated in Figures 2 and 3 of the drawings. As indicated in Figures 1 and 2 the articles to be displayed, such as Christmas tree balls or the

like 34 have their hangers 35 engaged over the hooks 33, with the largest balls resting on the top 6 of the base, and with the next smaller size of balls resting against each other and upon the larger balls below, and against the upper part of the combined hanger and reflector, according to the sizes of the balls or other similar objects of generally similar nature which normally have light passing and diffusing or reflecting properties. The articles 34 are to be piled according to their decreases in size, upon the next lower and larger sizes, around the post 17 as indicated in Figure 1 of the drawings so as to form a pyramid or cone. In this arrangement when the bulb 10 is alight, the light emitted by the bulb will pass through the openings 31 in the combined hanger and reflector and pass through and on to the balls or other articles 34 and also be transmitted, diffused, and reflected through the base 5 and directly upwardly along the post 17, so as to give attractive, decorative, and novel lighting effects endowing the entire display with unusual attractiveness.

Referring now to the embodiment of the invention shown in Figures 7, 8 and 9, this comprises a base 5a which is generally similar to the base 5 except that around the opening 9a the top 6a is provided with a cylindrical collar 35 of the same material as the base. In view of this provision the combined hanger and light reflector of the first described embodiment is omitted, although the illuminating unit including the bulb 10a, the socket 11a and the display post 15 and the display post guide 16 are present and have the lower ends of their legs inserted in openings 12a in the base portion 12a of the bulb socket. The collar 35 has light emitting openings 36 which are vertically elongated and circumferentially spaced around the collar, and the post 11a has telescoped thereon a plurality of tubular sections 37 of light transmitting or reflecting material. Between adjacent sections circular hangers 38 are placed snugly on the post 11a, with the adjacent ends of the sections bearing on the top and bottom of the hanger as indicated in Figure 9 to support the same at the desired elevation above the collar 35 and above the next lower hanger.

The hangers 38 comprise flat annuli 39 and intersecting diametrical arms 40 and 41 which intersect at the center of the annulus as indicated by the numeral 42, the said center being provided with the small hole 43 which snugly receives the post 11a. The peripheral edge of the annular portion 39 is provided at suitable circumferentially spaced intervals with hooks 44 on which the hangers 45 of the shining articles 34a are suspended, so that the articles depend around the peripheral edge of the hangers.

As in the first described embodiment the larger ones of the articles 34a are placed lowermost and to rest on the top of the base 5a, while upwardly the articles are reduced in size, as are the hangers 38, and spaced to allow the articles to rest on the next below hanger, all as clearly shown in Figure 7 of the drawings. A suitable pinnacle 46 may be placed on the upper end of the rod 11a.

Although I have shown and described herein preferred embodiments of the invention, it is to be understood that I do not wish to limit the application of the invention thereto except as may be required by the scope of the subjoined claims.

Having described the invention, what is claimed as new is:

1. An ornamental device comprising a hollow

translucent base for resting on a supporting surface, said base being formed with a centralized opening, a light passing cylinder rising above said base around said opening, a post rising through said opening and cylinder to a point above said base, said post having a foot to rest upon said supporting surface, a brace having laterally extended portions secured to said foot on opposite sides of the post, said brace having an upper part supportably engaged with said post for bracing the post, said base having an upper area surrounding said opening for supporting articles to be displayed around said cylinder, and a light source in said opening.

2. An ornamental device comprising a hollow translucent base for resting on a supporting surface, said base being formed with a centralized opening, a light passing cylinder rising above said base around said opening, a post rising through said opening and cylinder to a point above said base, said post having a foot to rest upon said supporting surface, a brace having laterally extended portions secured to said foot on opposite sides of the post, said brace having an upper part supportably engaged with said post for bracing the post, said base having an upper area surrounding said opening for supporting articles to be displayed around said cylinder, and a light source in said opening.

3. A display device comprising a base for resting on a supporting surface, said base being formed with a centralized opening, a support on said surface beneath said opening, a display post rising above said base, said post having a lower part supportably connected to said support, a display post guide having a lower part supportably connected to said support, said guide having an upper part supportably engaged with said post for bracing the post, said base having an upper area surrounding said opening for supporting articles to be displayed around said post, a light passing cylindrical form rising around said opening in the base, said cylindrical form being formed integral with the base, and a light source in said opening.

4. An ornamental device comprising a hollow translucent base for resting on a supporting surface, said base being formed with a centralized opening, a light passing cylinder rising above said base around said opening, a post rising through said opening and cylinder to a point above said base, said post having a foot to rest upon said supporting surface, a brace having laterally extended portions secured to said foot on opposite sides of the post, said brace having an upper part supportably engaged with said post for bracing the post, said base having an upper area surrounding said opening for supporting articles to be displayed around said cylinder, said cylinder being removably inserted in said centralized opening in the base and provided with article hanging hooks around its upper end, and a light source in said opening.

5. A display device comprising a base for resting on a supporting surface, said base being formed with a centralized opening, a light passing tubular form concentric with said opening, a post rising through said opening and tubular form to a point above said base, said post having a foot rest upon said supporting surface, a brace having laterally extended portions secured to said foot on opposite sides of the post, said brace having an upper part supportably engaged with said post for bracing the post, said

base having an upper area surrounding said opening for supporting articles to be displayed around said cylinder, said display post comprising a metallic rod, and a light source in said opening.

6. A display device comprising a base for resting on a supporting surface, said base being formed with a centralized opening, a support on said surface beneath said opening, a display post rising above said base, said post having a lower part supportably connected to said support, a display post guide having a lower part supportably connected to said support, said guide having an upper part supportably engaged with said post for bracing the post, said base having an upper area surrounding said opening for supporting articles to be displayed around said post, said display post comprising a rod, vertically separated tubes telescoped thereon with dish-like horizontal hangers disposed on the rod and between adjacent ends of the tubes, said hangers having article hanging hooks at their outer edges.

7. A luminous ornamental device comprising a hollow translucent base formed with a central opening, means supported in said opening and comprising a plate having a light source rising therefrom, a post comprising lower elements supportably connected to said plate on opposite sides of said light source and a rod rising above said elements to a point substantially elevated above said base, a light passing cylindrical form rising around said opening in the base and enclosing said lower elements and said light source.

8. A luminous ornamental device comprising a hollow translucent base formed with a central opening, means supported in said opening and comprising a plate having a light source rising therefrom, a post comprising lower elements supportably connected to said plate on opposite sides of said light source and a rod rising above said elements to a point substantially elevated above said base, a light passing cylindrical form rising around said opening in the base and enclosing said lower elements and said light source, said cylindrical form being removably inserted in said opening and having a portion surrounding said plate.

9. An ornamental device comprising a relatively flat hollow translucent material base adapted to rest on a supporting surface, said base

being formed in its top with an opening, a light passing tube registered with said opening and rising above the top of the base, a plate adapted to rest on said supporting surface, a light source on the top of said plate and arranged to project light through said base and through the side walls and open upper end of said tube, a post rising through said tube to an elevated point above said tube, said post comprising elements on its lower end supportably engaging said plate on opposite sides of said light source.

10. An ornamental device comprising a relatively flat hollow translucent material base adapted to rest on a supporting surface, said base being formed in its top with an opening, a light passing tube registered with said opening and rising above the top of the base, a plate adapted to rest on said supporting surface, a light source on the top of said plate and arranged to project light through said base and through the side walls and open upper end of said tube, a post rising through said tube to an elevated point above said tube, said post comprising elements on its lower end supportably engaging said plate on opposite sides of said light source.

11. An ornamental device comprising a relatively flat hollow translucent material base adapted to rest on a supporting surface, said base being formed in its top with an opening, a light passing tube registered with said opening and rising above the top of the base, a plate adapted to rest on said supporting surface, a light source on the top of said plate and arranged to project light through said base and through the side walls and open upper end of said tube, a post rising through said tube to an elevated point above said tube, said post comprising elements on its lower end supportably engaging said plate on opposite sides of said light source, and a plurality of ornamental light reflecting objects resting on the top of said base and against the sides of said tube and against the sides of said post and receiving light from said light source.

12. An ornamental device comprising a relatively flat hollow translucent material base

FRANK PIERCE MORTIMER.
